UNITED STATES PATENT OFFICE.

ALBERT EDWARDS, OF BROOKLYN, NEW YORK.

APPARATUS FOR COATING SURFACES.

SPECIFICATION forming part of Letters Patent No. 358,849, dated March 8, 1887.

Application filed June 26, 1886. Serial No. 206,329. (No model.)

To all whom it may concern:

Be it known that I, ALBERT EDWARDS, a citizen of the United States, residing at Brooklyn, in the county of Kings and State of New York, have invented a new and Improved Process of and Apparatus for Coating Surfaces of Textile Material, of which the following is a specification.

My invention relates to an improved process 10 of and apparatus for coating surfaces; and the objects of my improvements are, first, to provide a simple process whereby the under surfaces of articles—such as gimp, braids, &c.—can be coated with any glutinous substance 15 without the liability of the mixture penetrating more than will be necessary for adhesion; second, to afford a means for coating such surfaces with expedition, so that the cost of the article so treated will not be materially increased; and, third, to provide as an article of 20 merchandise gimp, braids, &c., prepared with an adhesive surface, whereby they can be applied to articles of furniture by simply moistening the said surface and bringing it in contact with such article, thus making a great 25 saving in time and expense of applying the same. I accomplish these objects by the mechanism illustrated in the accompanying drawings, in which—

Figure 1 is a perspective view of the machine. Fig. 2 is a plan view of the article coated; and Fig. 3, a plan view of a modification of the device, which represents a flat surface with the ribs running parallel with each 35 other.

The process consists of first coating a smooth hard raised surface, resembling a rib, with a glutinous substance and allowing it to become set to the proper consistence, but not to render 40 it unpliant. The surface of the article to be coated is then placed on the glutinous substance and subjected to slight pressure, thereby causing the rough or uneven surfaces of the article to be pressed into the soft glutinous substance, 45 which slightly enters the texture and adheres to it. At the proper time the article is removed from the smooth hard surface, carrying with it the glutinous substance, which forms a smooth glossy coating on the under surface of the article so treated. The width of the rib is preferably made narrower than the article coated,

thus leaving a margin on each edge which is not coated on said article. The smooth hard surface causes the glutinous substance to assume a close even surface. Consequently there 55 is but slight adhesion to it, and therefore readily stripped off when dry, as it closely adheres to the softer texture of the article coated.

The device for coating surfaces consists, preferably, of a cylinder, B, supported by a frame, 60 A, said cylinder having a continuous rib, P, winding round it spirally at a constant inclination, so as to leave a like continuous groove, S, between each turn and the next, thus providing a continuous surface of great length, 65 and yet within narrow limits. This cylinder also produces, when revolved, motion or pressure in the direction of its length, and thereby imparts motion to two carriages, D F, which are provided with wheels N, adapted to fit 70 into said groove S.

The carriage F is supported on rod C, and is provided with a receptacle, I, for holding the glutinous substance, and carries a brush, L, which is caused to bear and distribute the glutinous substance onto the said ribs P. Said carriage is also provided with a pendant or wheel, N, which runs in groove S, having its bearing against the side of rib P, and by which motion is imparted to it when the cylinder is revolved, 80 causing it to travel in the direction of the length of said cylinder, and thereby spreading the glutinous substance over the entire rib surface.

The carriage D is supported on the rod C', and is provided with a pendant or wheel, N, 85 which is adapted to run in groove S, having its bearing against the side of the rib, and by which motion is imparted to it when the cylinder is revolved, causing it to travel in the direction of the length of said cylinder, and 90 thereby carrying the article to be coated along with it, and directing said article, by the aid of guide H, onto the rib P of said cylinder B.

The article coated is subjected to more or less tension, which compresses it to the cylinder as 95 it is wound on the same. The cylinder is revolved by any mechanical device. The ribs can be coated with the glutinous substance by hand, if desired.

I am aware that it is common to use glue in 100 attaching gimp to articles of furniture; but it is applied with a brush and at the time when

it is to be attached to any article. This method is objectionable, as the glue is liable to extend over the edge and disfigure the gimp, besides some styles of gimp will not permit the brush to 5 be used for fear of the glue passing through the meshes. This, therefore, I do not claim; but I am not aware that a preparation of glue has been spread on a surface and allowed to become properly set, and then pressing the article to be coated onto the said glutinous surface, and at the proper time stripping the article off, bringing the glutinous substance with it, before my invention.

I do not wish to be understood as confining 15 myself to a narrow raised surface for spreading the glutinous substance on, as I can use a broad flat surface when wide articles are to be coated singly equally as well.

What I claim, and desire to secure by Letters Patent, is—

1. The method of coating articles described, consisting in coating a smooth hard surface

with a glutinous substance and allowing it to become set to a proper consistence, then placing the article to be coated on the said glutinous substance and subjecting it to slight pressure, thereby causing the rough or uneven surface to be pressed into the soft glutinous substance, which slightly enters the texture and adheres to it, then stripping the article from 25 the surface, carrying with it the glutinous substance, which forms a smooth glossy coating on the under surface of the article so treated, as set forth.

2. In an apparatus for coating surfaces, the cylinder B, provided with rib P, groove S, and the means for guiding the article to be coated onto said cylinder, substantially as and for the purpose set forth.

ALBERT EDWARDS.
